ABSTRACT OF THE DISCLOSURE

A downspout diverter consisting of a vertical conduit with a pivot pin spanned across it and a channel with a reciprocal spiral slot on each of its walls, the slot pivotable about said pin to form a flow diverter.

This invention relates to a device for diverting liquid flow, and more particularly to a flow diverter of novel, simple design which can be incorporated into any conduit type system such as a roof drainpipe for diverting liquid flow.

Diverters are not broadly new. For example, U.S. Patent 117,493 teaches such a diverter for drain pipes. Unfortunately, the diverter requires a special complicated, box-type structure. Its complexity as well as its obvious high cost of fabrication and installation makes it unattractive for popular use.

U.S. Patent 124,053 teaches an improvement, but it too, as one brief glance at the drawing will reveal, is somewhat complex.

U.S. Patent 1,217,938 shows a valve for suction or blower conduits. But this valve requires the use of side plates, as well as a separate locking device. Complex overlapping of parts is also required to prevent leakage and this further complicates the structure.

An object of this invention is to provide a flow diverter of simplified design and construction.

Another object is to provide a diverter of the above character capable of altering the flow path of a liquid from its normal path to an alternate path.

Still another object is to provide a diverter of the above character which effectively and substantially seals off the normal path when used to divert such path of flow.

A further object is to provide a diverter which can channel a liquid flow to cause it to pour into a storage device such as a cistern.

A still further object is to provide a diverter of the above character for a drainpipe which is easily installed.

Another object is to provide a diverter of the above character which is simple in structure.

Another object is to provide a diverter of the above character which blends into the drainpipe when not in use for a neater appearance.

Another object is to provide a diverter of the above character which is substantially foolproof in operation.

Another object is to provide a diverter of the above character which is simple to fabricate.

Another object is to provide a diverter of the above character which is durable.

Other objects of the invention will in part be obvious and will in part appear hereinafter.

A novel device has now been devised which satisfies the above objectives. It comprises a vertical conduit and a slotted bipositional channel; the channel being mounted on a pivot pin affixed to the conduit. The slot has the general form of a reciprocal spiral. When the channel is in the closed, or undiverting position, it forms a section of the conduit wall. In the diverting position, which is accomplished by rotating the channel about the pivot pin until the channel seals off the main path of flow of the

2

conduit, substantially complete diversion of the liquid flow is accomplished.

The invention accordingly comprises the features of construction, combination of elements, and arrangement of parts which will be exemplified in the construction hereinafter set forth, and the scope of the invention will be indicated in the claims.

For a fuller understanding of the nature and objects of the invention, reference should be had to the following detailed description taken in connection with the accompanying drawing in which:

FIG. 1 is a perspective view of the diverter of this invention showing it employed as a downspout diverter for the rainwater runoff system of a building.

FIG. 2 is a vertical cross-sectional view of the diverter in the closed position.

FIG. 3 is a vertical cross-sectional view of the diverter in the open, or diverting, position.

Similar reference characters refer to similar parts throughout the several views of the drawing.

With special reference to FIGS. 2 and 3, it can be seen that the diverter of this invention is comprised of a vertical conduit 10, a slotted bipositional channel 20, and a pivot pin 24. The ends 11 of conduit 10 are shaped for easy insertion into the vertical conduit. Usually, such is accomplished by corrugating the ends. The pivot pin 25 is mounted, and extends diametrically through the exterior side walls of the vertical conduit 10, and also through the slot 30 of the bipositional channel 20.

It can best be seen in FIG. 2, that is the closed position, the slotted channel 20 serves as a portion of side wall 12 and a portion of the face wall 14, and the back wall (not shown) of the vertical conduit 10. In this position, the channel 20 and vertical conduit 10 forms a composite closed duct. The flow is thereby confined to the vertical or normal pathway 16. The edges of the walls of the channel fit into cutouts 13 (only one shown) in conduit 10.

In order to divert the flow, it is only necessary to place the slotted channel in the open position. This is accomplished by grasping the channel near its uppermost extremity 27 and lifting it. Such movement will cause the channel 20 to slide along the pivot pin, decreasing the distance between the pin 25 and the lower extremity 28 of the channel 20. The channel 20 is then rotated in a clockwise manner about the pin until it is perpendicular to the vertical duct. The pivot pin will then be at point A along slot 30. As the channel is further rotated in a clockwise manner, the slot 30 continues to slide on the pivot pin until the pin is at point B. The channel can then be lowered causing the pin to be positioned at the endmost extremity C of slot 30. Further rotation of the channel causes the extreme edge 31 of the diverting surface to come into sealing contact with the interior surface 40 of vertical conduit 10, thereby completely blocking the normal path of flow. In this position, the lower surface of the channel is supported by edge 42.

It is worthy of mention that while the opening process is described in a sequential manner, this is done to increase the clarity of description only. The actual opening of the physical device can be considered as one continuous process.

When the diverter is in the open position, substantially all liquid flowing from the upper portion of the vertical conduit will be deflected to exit at channel end 36.

The net result of the weight of the fluid in the channel will be to produce a net moment about the pin in a clockwise manner, thereby requiring that the diverting surface 32 will be held firmly in contact with the interior wall of the vertical conduit 10. This will minimize leakage into the normal pathway at this point.

The construction of this invention is such as to provide a simple mechanism which is easily fabricated by two

separate forgings, stampings, or similar processes and is readily assembled by the simple insertion of a pivot pin.

Ease of installation is provided by the nature of the device which may be considered to be another section of the ducting, and in application, may actually be such.

It is preferred that the diverter be constructed of corrosion resistant material such as zinc plated sheet steel, sheet aluminum and the like. Since it has few moving parts, wear will be kept to a minimum. And, since its structure is so simple, its cost will be only slightly more than the cost of the section of conduit it replaces. It should be evident that it is easily fabricated. It may be installed by simple replacement of a section of drainpipe.

It will thus be seen that the objects set forth above, among those made apparent from the preceding description, are efficiently attained, and, since certain changes may be made in the above construction without departing from the scope of the invention, it is intended that all matter contained in the above description or shown in the accompanying drawing shall be interpreted as illustrative and not in a limiting sense.

Now that the invention has been described, what is claimed is:

1. A device for diverting liquid flow comprising a vertical conduit with a pivot pin affixed thereto and a biposi- 25

tional channel with a slot on each of its walls, said slot having the general form of a reciprocal spiral, said channel being reciprocal upon said pivot pin via said slot.

2. The device of claim 1 wherein said channel in closed position forms a section of the wall of said conduit.

3. The device of claim 1 wherein said channel in open position substantially seals off the main path of flow through said conduit via an edge which comes into substantial sealing contact with the interior surface of said conduit.

4. The device of claim 1 wherein said conduit has open corrugated ends for ready insertion into a drainpipe.
